UNITED STATES PATENT OFFICE

148,277

DESIGN FOR A PIN

Herman Bogoff, Chicago, Ill.

Application October 14, 1946, Serial No. 133,928

Term of patent 7 years

(Cl. D45—19)

To all whom it may concern:

Be it known that I, Herman Bogoff, a citizen of the United States, residing in Chicago, in the county of Cook and State of Illinois, have invented a new, original, and ornamental Design for a Pin, of which the following is a specification, reference being had to the accompanying drawing, forming part thereof.

Fig. 1 is a front elevational view of a pin showing my design, and

Fig. 2 is the side view thereof.

I claim:

The ornamental design for a pin, substantially as shown.

HERMAN BOGOFF.
